United States Patent Office

Des. 184,978
Patented Apr. 28, 1959

184,978

COMBINED TABLE AND AQUARIUM

Edwin R. Britton, Brownstown, Ill., and Neil H. McKernan, Martinsville, Ind.

Application September 4, 1958, Serial No. 52,508

Term of patent 14 years

(Cl. D33—14)

FIG. 2.

FIG. 3.

We claim:

The ornamental design for a combined table and aquarium, as shown.
